TIRE

Ben S. Mattingly, 304 E. Mount Vernon St., Somerset, Ky.

Filed Apr. 28, 1960, Ser. No. 60,351

Term of patent 3½ years

(Cl. D90—20)

FIG 1

FIG. 2

FIG. 3

FIG. 4

FIG. 5

Fig. 1 is a perspective view of a tire showing my new design, it being understood that the full-line portions of the design are repeated throughout the circumference of the tire shown by means of broken lines;

Fig. 2 is an enlarged fragmentary top plan view thereof;

Fig. 3 is a fragmentary side elevational view thereof on a slightly reduced scale;

Fig. 4 is a cross-sectional view thereof taken on line 4-4 of Fig. 2, but on a reduced scale; and

Fig. 5 is a cross-sectional view thereof taken on line 5-5 of Fig. 2, but on a reduced scale, the bottom portion of the tire being omitted for convenience of illustration.

The dominant features of my design reside in the full-line portions of the drawings above the buttress ribs.

I claim:

The ornamental design for a tire, as shown and described.
